UNITED STATES PATENT OFFICE.

CHARLES H. SHEPARD, OF BROOKLYN, NEW YORK, ASSIGNOR TO WYCKOFF, SEAMANS & BENEDICT, OF ILION, NEW YORK, A CORPORATION OF NEW YORK.

TYPE-WRITING MACHINE.

SPECIFICATION forming part of Letters Patent No. 749,106, dated January 5, 1904.

Application filed November 7, 1901. Serial No. 81,421. (No model.)

To all whom it may concern:

Be it known that I, CHARLES H. SHEPARD, a citizen of the United States, and a resident of the borough of Brooklyn, city of New York, 5 in the county of Kings and State of New York, have invented certain new and useful Improvements in Type-Writing Machines, of which the following is a specification.

My invention relates to tabulating mechanism for type-writing machines and is shown in its application to a No. 6 Remington machine, though obviously it may be applied to any type-writing machine wherein it may be found available.

15 In tabulating devices heretofore devised the construction has usually been such that if the operator actuates a key to project a tabulating-stop and to simultaneously release the carriage and immediately thereafter removes 20 the finger from the key there is a liability of the carriage being reengaged by the feed mechanism before the carriage reaches the proper position as determined by the tabulating-stops, so that the tabulating mechanism is 25 ineffective to accomplish its purpose. It is likewise true that in such prior devices it often occurs that the impact of the carriage against the tabulating-stop causes the carriage to jump back one, two, or more letter- 30 space distances and a reengagement of the carriage with its feed mechanism is liable to be effected before the carriage has an opportunity to settle back to the proper position where it was intended to be arrested. The 35 consequence of this is that the carriage instead of being arrested at the proper position as determined by the tabulating-stops will be arrested at one, two, or more letter-space distances to the right of said position, and this 40 fact if not observed by the operator will result in the figures being written in the wrong column.

The object of my invention is to overcome these and other disadvantages in tabulating 45 devices heretofore devised and to produce a simple and efficient tabulating device wherein means are provided to assure the proper operation of the tabulating device under all conditions.

50 To these and other ends, which will herein-

after appear, my invention consists in the novel arrangements and combinations of parts to be hereinafter described, and particularly pointed out in the concluding claims.

In the accompanying drawings, wherein like reference characters represent corresponding parts in the various views, Figure 1 is a vertical sectional view of one form of type-writing machine embodying my invention, the section being taken from front to rear of the 55 machine. Fig. 2 is a plan view of the same. Fig. 3 is an enlarged detail side view of a portion of one form of tabulating mechanism to be hereinafter more fully described. Fig. 4 is a like view of the same with a denominational stop shown in the projected position and the retarding device engaged thereby. Fig. 5 is a like view of the same with the parts shown in the position where a denominational stop is about to free itself from engagement with the retarding mechanism on the return movement of the projected stop. Fig. 6 is a top view of the parts shown in Figs. 3, 4, and 5. Fig. 7 is an isometric detail view of a portion of the device to be herein- 70 after described. Fig. 8 is a detail side view of a modified form of device embodying my invention, the parts being shown in the normal position. Fig. 9 is a like view of the same with the parts shown in the working 75 position. Fig. 10 is a front view of the parts shown in Figs. 8 and 9 with the tabulating-stop on the carriage omitted.

In the various views parts are omitted and broken away to better illustrate other parts 80 of the structure.

Referring particularly to Fig. 1 of the drawings, 1 indicates the framing of the machine, in which the usual or any suitable key-levers 2 are mounted, each key-lever being provided with a finger-key 3. Extending beneath the key-levers 2 is a universal bar 4, which is connected at each end to a link 5, which links in turn are connected to a bowed bar 6, that is secured to an arm 7, which projects from the 95 rock-shaft 8 of the dog-rocker 9. This dog-carrier carries the usual or any preferred feed-dogs 10, which co-operate with a feed-wheel 11, that is operatively connected to a rock-shaft that turns in suitable bearings 12, (see 100

Fig. 2,) secured to the top plate 13, as shown at 14. The opposite end of this shaft, to which the feed-wheel 11 is operatively connected, may be provided with a feed-pinion 15, that 5 meshes with a rack 16, carried upon arms 17, that are pivoted at 18 to a carriage 19, so that the rack is capable of being elevated to disengage it from the feed-pinion, and thereby enable the carriage to be moved freely in 10 either direction. The carriage 19 is provided with suitable traverse-rollers 20 and 21, which bear, respectively, upon a traverse-rod 22 and a shift-rail 23. The carriage 19 carries the usual platen 24 for holding the paper to be 15 struck by the type-bars 25, which are pivoted to bangers secured to the top plate 13 and operated by rods 26, connected to the key-levers, as usual.

Projecting rearwardly from the carriage 19 20 are supporting-arms 27, which have secured to their rear ends a rack-bar 28, which supports one or more adjustable tabulating-stops 29, as customary. Beneath the bank of finger-keys 3 is a series of push-rods 30, each 25 having a push-key 30^X and a returning-spring 31, which is secured at one end to a fixed portion of the machine, as 32, and at the other end to a collar 33 on the push-rod 30. The rear end of each push-rod is connected at 34 30 to an upwardly-extending lever 35, that is pivoted at 36 to a frame 37, that may be secured to the framing 1 of the machine. The upper end of each of these levers 35 is pivotally connected to a movable denominational 35 stop, which is apertured at 39 to receive the fixed guiding-rods 40, which guide the stops in their movement and limit the rearward and forward movement thereof. Each of the stops 38 is provided with a shoulder 41, which is 40 adapted to contact with a bar 42, that extends across the series of stops, as represented in Fig. 2, and is provided with depending arms 43, which are pivoted at 44 to the frame 37. One of these depending arms 43 is provided with a forwardly-extending arm 45, which is connected at 46 to a link 47, which is pivoted at 48 to a lever 49, fulcrumed at 50 in a bracket 51, that is secured at 52 to the top plate of the machine. The forwardly-extending end of the lever 49 is provided with 55 a flattened surface or shoe 53, which is adapted to be forced into contact with the rack-bar 16 and to lift it out of engagement with the pinion 15. Each of the stops or blades 38 is provided at its underface with an inclined portion or cam 54 forward of a notch 55, formed in the stop. The cam and the notch of each stop are adapted to coöperate with a cross-bar 56, (see Fig. 7,) that is connected at its ends 60 to depending spring-pressed plungers 56^X, the reduced stem 57 of each of which is provided with a laterally-extending pin 58, that projects through an aperture 59 in the recessed end of a lever 60 in order to limit the upward movement of the plunger with relation to said lever. The plungers and the cross-bar 56 are maintained normally in the raised position by

two coiled springs 61, each of which is contained within a recess in a lever 60 and bears at one end upon the shoulder of the plunger 70 and at its opposite end against the bottom of the recess in the lever. One of the levers 60 is pivoted at 62 to a plate 63, which is secured to one side of the frame 37. The other lever, 60, is pivoted to a bracket 60^X, projecting 75 from the opposite side of the frame 37. (See Fig. 2.) This lever 60 on the plate 63 has pivoted thereto at 64 and intermediate of the ends thereof a link 65, which in turn is pivoted at 66 to a second link 67, that oscillates 80 on a pivot 68. Pivoted to the link 67 is a gravity-pawl 69, that coöperates with the teeth of a ratchet-wheel 70, and this ratchet-wheel has secured thereto a pinion 71, which meshes with a gear-wheel 72, that has secured 85 thereto or formed therein an internal or grooved cam 73. Projecting into the groove of this cam is a pin 74, which is carried by an arm or rod 75, which is pivoted at 76 to the plate 63 and carries a weight 77 at its 90 lower end, which weight may be adjusted along the arm or rod 75 and maintained in the adjusted position by a set-screw 77^X. The adjustment of the weight enables it to be moved to varying distances from the pivot 95 76 of the rod, thus providing a regulating means by which the weight is rendered effective to retard the return movement of the parts to a greater or less degree, according to the adjustment of the weight. The rod 75 100 may likewise be provided with a thin portion 75^X which is highly flexible or elastic, so that when the rod 75 is vibrated by the cam 73 the weight may receive a movement around the flexible portion 75^X independently of the 105 upper pivoted part of the rod, thus tending to further retard the return movement of the projected denomination-stop and the parts controlled thereby.

The lever 60 and the parts connected thereto are normally maintained in the forward position by a spring 78, which is secured at one end 79 to said lever and at its opposite end 80 to the plate 63. The forward movement of these parts is limited by a pin-stop 81, with 115 which the lever 60 contacts. Upon reference to Figs. 3 to 7 it will be observed that the bar 56 extends beneath all of the denominational stops 38, so that it may coöperate with any one of them in the forward movement of said 120 stops.

When any push-key 30^X is forced rearwardly, as indicated by the arrow in Fig. 1, the lever 35 will be moved around its pivot, thus moving the coöperating denominational 125 stop 38 to the projected position, where it will be interposed in the path of the stop 29 on the carriage. This forward movement of a denominational stop 38 will cause the bar 42 to be moved with it, thereby depressing the 130 forward end of the arm 45, and this movement is effective to turn the lever 49 on its pivot, thereby raising the rack 16 out of engagement with its feed-pinion 15. The car-

riage being thus freed from its feed mechanism is moved in the direction of its feed by the spring-drum 82, it being understood that the usual connecting-band 83 between the carriage and spring-drum is employed. The movement of the carriage will continue until the tabulating-stop 29 reaches contact with the stop 38, which has been projected into its path by the operation of the push-key 30^X.

10 During the forward movement of any denominational stop 38 from the position indicated in Fig. 3 to the position illustrated in Fig. 4 the cam-face 54 upon said stop will contact with the bar 56 and force the bar downwardly until the bar is opposite the notched or recessed portion 55 in the stop, when the springs 61 of the bar 56 will force it into said notch and behind the shoulder formed by the forward wall thereof, as represented in Fig. 4.

15 When the finger of the operator is released from the push-key 30^X, the spring 31 thereof tends to restore all of the parts to the normal position—that is to say, this spring tends to restore the denominational stop 38 to its

20 normal position and to simultaneously permit the rack 16 to engage its coöperating pinion 15. In the movement of the denominational stop 38 from the position shown in Fig. 4 to that illustrated in Fig. 3 the bar 56, being in engagement with the stop, will be vibrated, and the pawl 69 will turn the ratchet-wheel 70 in the direction of the arrows in Figs. 4 and 5. This movement of the ratchet-wheel is transmitted to the cam 73, which

25 causes the weight to be oscillated, and the power required to bring about these various movements is sufficient to retard the movement of the stop 38 and the parts operatively connected thereto in their movement to the

30 normal position.

It will be seen that the parts just described in effect constitute a counteracting or retarding device for limiting the speed of the return movement of the projected stop and for 45 retarding the reengagement of the rack 16 with its feed-pinion, so that should the operator actuate one of the push-keys 38 and release it before the tabulating-stop 29 has reached contact with the projected denominational stop 38 a proper operation of the device may nevertheless be assured, because of the retardation in the movements of the denominational stop and feed-rack to their normal positions.

50 When the carriage-stop 29 strikes a denominational stop, the carriage will usually rebound, the extent of the rebound depending upon the distance the carriage has traveled, or, in other words, upon the striking force of the stop 29 against the stop 38, the carriage jumping back from one space to perhaps half a dozen letter-spaces; but in the present machine, owing to the slow return of the parts to normal position, the stop 55 38 will still be in a projected condition and the rack will be out of engagement with its pinion when the carriage recovers from the

rebound and starts forward again, and hence the stop 29 and the carriage will eventually be arrested at the point predetermined by 70 the setting of the stops, and there is no liability of the carriage reengaging with the escapement mechanism and being arrested on the rebounding action or recovering action at an improper point or at a place to the right 75 of that provided for by the setting of the stops.

Upon reference to Figs. 8, 9, and 10 of the drawings it will be seen that a modified form of structure is employed wherein each of the 80 levers 35, that actuate the denominational stops 38, has pivoted thereto at 89 a toothed pawl or rack 90. This rack is provided with a series of rearwardly-projecting teeth 91 and is maintained by its own weight against 85 a stop 92, whereas a stop 93 may be employed to limit the upward movement thereof. Each of these pawls or racks 90 coöperates with an elongated ratchet-wheel 94, whose shaft 95 is supported in bearings 96 on the denominational-stop frame 37, and one end of this shaft 95 has secured thereto a fly-wheel 98. The teeth on the ratchet-wheel 94 are so disposed that in the forward movement of any of the pawls or racks 90 no motion will be 90 transmitted to the ratchet-wheel and its connected fly-wheel. Thus when a push-key has been actuated to move one of the levers 35 forward the coöperating rack 90 will ride over the teeth on the ratchet-wheel; but as soon as the stop 38, the lever 35, and the various parts operatively connected thereto start to return to the normal position the teeth 91 engage the teeth of the ratchet-wheel and the pressure of the spring 31 of 105 the push-key, which tends to restore these parts to the normal position, will be counteracted by the weight of the fly-wheel, so as to retard the return movement of the parts. While the construction of the fly-wheel or 110 weight 98 and the parts directly coöperating therewith are somewhat different from the weight 77 and the parts directly coöperating therewith, nevertheless it will be seen that in both cases a device is provided to retard 115 the movement of the stop from the projected position and to retard the reengaging movement of the carriage-feeding devices.

While I have shown and described two forms or devices embodying my invention, it should be understood that various changes may be made without departing from the spirit of the invention, and that any one or more of the features thereof may be employed without the others.

125 Although I have shown my invention carried out in a machine wherein the carriage is arrested at different denominational positions, it will be understood that my improvements may be embodied in machines wherein 130 the carriage is arrested always at one or more positions to determine simply the starting-point of the column or columns to be written. For example, instead of a set of denomina-

tion-stops such as shown there may be only a single stop, as 38, to determine the columnar position of the carriage.

5 The means for retarding the return movement of the stop and also the reengaging operation of the carriage feeding or escapement devices are controlled by each of the keys 30^x in such a way that said retarding means may operate only after the removal of pressure 10 from the particular key actuated.

15 My improvements comprise means for enabling a tabulating-stop to be freely projected, but acting to retard said stop in its return movement. It also comprises means for 20 retarding the reengaging operation of the coöperating carriage-feed devices, and in carrying out my invention in connection with the numerous varieties of tabulating mechanisms and feed mechanisms which have 25 heretofore been devised and to which my improvements are generally applicable it is evident that many changes in details of construction and arrangement of parts will be necessary; but these may be readily made 30 without departing from the gist of my invention.

It will be observed that when the carriage 35 is released and the stop or blade is projected the parts are not locked in this abnormal or 40 working condition and subsequently unlocked, as in some prior machines, because the maintenance of the feed-rack out of mesh with the feed-pinion and the stop or blade in projected position is dependent wholly upon 45 the pressure on the key 30^x by the finger of the operator, the construction and arrangement being such that when the key is relieved of pressure the rack and stop are free to return to their normal positions; but in their 50 return movements they have a slowed-down or retarded movement, owing to the automatic coupling or connecting therewith of the aforesaid retarding devices.

What I claim as new, and desire to secure 55 by Letters Patent, is—

1. In a tabulating device for type-writing machines, the combination of a carriage, a stop carried by said carriage, a second stop co-operating with the carriage-stop, said stops 60 being normally out of the path of each other, means for projecting one of said stops into the path of the other, and means for limiting the speed of the return movement of the projected stop.

2. In a tabulating device for type-writing machines, the combination of a carriage, a stop carried by said carriage, a second stop co-operating with the carriage-stop, said stops being normally out of the path of each other, 65 spring-restored means for projecting one of said stops into the path of the other and means for counteracting the spring-restored means to retard the speed of the projected stop.

3. In a tabulating device for type-writing machines, the combination of a carriage, a stop carried by said carriage, a second stop

which coöperates with the carriage-stop and is carried by the frame of the machine, said stops being normally out of the path of each other, key-actuated means for projecting one of said stops into the path of the other and means for retarding the speed of the return movement of the projected stop.

4. In a tabulating device for type-writing machines, the combination of a carriage, a stop carried by said carriage, a second stop coöperating with the carriage-stop, said stops being normally out of the path of each other, means for projecting one of said stops into the path of the other, and automatically-operated means for retarding the speed of the return movement of the projected stop.

5. In a tabulating device for type-writing machines, the combination of a carriage, a tabulating-stop therefor, a denominational stop coöperating with the tabulating-stop, said stops being normally out of the path of each other, means for projecting said denominational stop into the path of the tabulating-stop, and means for retarding the speed of the return movement of the denominational stop.

6. In a tabulating device for type-writing machines, the combination of a carriage, a tabulating-stop carried by said carriage, a denominational-stop carried by the frame of the machine, said stops being normally out of the path of each other, key-actuated means carried by the frame of the machine for projecting said denominational-stop into the path of the tabulating-stop, and automatically-operated means for retarding the return movement of the projected stop.

7. In a tabulating device for type-writing machines, the combination of a carriage, an adjustable tabulating-stop carried by said carriage, a denominational-stop carried by the frame of the machine, said stops being normally out of the path of each other, spring-restored key-actuated means carried by the frame of the machine for projecting said denominational-stop into the path of the tabulating-stop, and automatically-operated spring-restored means for retarding the return movement of the projected stop.

8. In a tabulating device for type-writing machines, the combination of a carriage, a tabulating-stop, a plurality of coöperating denominational stops, key-actuated means for projecting any of said denominational stops into the path of the tabulating-stop and means for retarding the speed of the return movement of any projected denominational stop.

9. In a tabulating device for type-writing machines, the combination of a carriage, a tabulating-stop, a plurality of coöperating denominational stops, key-actuated means for projecting any of said denominational stops into the path of the tabulating-stop and a single retarding device which coöperates with all of said denominational stops.

10. In a tabulating device for type-writing machines, the combination of a carriage, a

- tabulating-stop, a plurality of coöperating denominational stops, a separate spring-restored key for projecting each of said denominational stops into the path of the tabulating-stop, and a single automatically-operated retarding device which coöperates with all of said denominational stops.
11. In a tabulating device for type-writing machines, the combination of a carriage, a stop carried by said carriage, a second stop co-operating with the carriage-stop, said stops being normally out of the path of each other, means for projecting one of said stops into the path of the other, means for limiting the speed of the return movement of the projected stop, and means for disengaging the carriage from its feed mechanism during the movement of the projectable stop to projected position.
12. In a tabulating device for type-writing machines, the combination of a carriage, a stop carried by said carriage, a second stop co-operating with the carriage-stop, said stops being normally out of the path of each other, spring-restored means for projecting one of said stops into the path of the other, means for counteracting the spring-restored means to delay the projected stop when released and during its return movement, and means for disengaging the carriage from its feed mechanism during the movement of the projectable stop to projected position.
13. In a tabulating device for type-writing machines, the combination of a carriage, a stop carried by said carriage, a second stop which coöperates with the carriage-stop and is carried by the frame of the machine, said stops being normally out of the path of each other, key-actuated means for projecting one of said stops into the path of the other, means for retarding the speed of the return movement of the projectable stop, and means for disengaging the carriage from its feed mechanism during the movement of the projectable stop to the projected position and for reengaging the carriage with its feed mechanism during the retarded return of said stop to the normal position.
14. In a tabulating device for type-writing machines, the combination of a carriage, a tabulating-stop therefor, a denominational stop coöperating with the tabulating-stop, said stops being normally out of the path of each other, means for projecting the denominational stop into the path of the tabulating-stop, automatically-operated means for retarding the speed of the return movement of the denominational stop and means for disengaging the carriage from its feed mechanism during the movement of the denominational stop to its projected position.
15. In a tabulating device for type-writing machines, the combination of a carriage, a tabulating-stop, a plurality of coöperating denominational stops, key-actuated means for projecting said denominational stops into the path of the tabulating-stop, a single retard-
- ing device which coöperates with all of said denominational stops to retard their return movement from the projected position and means for automatically disengaging the carriage from its feed mechanism during the movement of any of the denominational stops to the projected position and for reengaging the carriage with its feed mechanism during the return of a projected stop to the normal position.
16. In a tabulating device for type-writing machines, the combination of a carriage, a stop therefor, a coöperating spring-restored stop, said stops being normally out of the path of each other, means for projecting the spring-restored stop into the path of the other stop, and means for automatically affording a resistance to the return of the spring-restored stop, such resistance being sufficient to retard but not to block the return movement of said stop.
17. In a tabulating device for type-writing machines, the combination of a carriage, a tabulating-stop therefor, a plurality of coöperating denominational stops, said denominational stops being spring-restored and normally out of the path of the tabulating-stop, means for projecting any of the spring-restored denominational stops into the path of the tabulating-stop, and means for automatically affording a resistance to the return of the spring-restored stops, such resistance being sufficient to retard but not to block the return movement of said stops.
18. In a tabulating device for type-writing machines, the combination of a carriage, a stop therefor, a coöperating spring-restored stop, said stops being normally out of the path of each other, means for projecting the spring-restored stop into the path of the other stop, means for automatically retarding the return of the spring-restored stop, feed mechanism for the carriage, and means controlled by the spring-restored stop for effecting a disengagement and reengagement of the feed mechanism.
19. In a type-writing machine and in a tabulating device, the combination with coöperating tabulating-stops, of a carriage, disengageable feed mechanism therefor, and means for automatically retarding the relative movement of the parts of the disengageable feed mechanism during the reengaging movement thereof.
20. In a type-writing machine and in a tabulating device, the combination of a carriage, a carriage-feed element carried by the carriage, a coöperating carriage-feed element on the frame of the machine, a tabulating-stop carried by the frame of the machine, a coöperating tabulating-stop carried by the carriage, means for projecting one of said stops into the path of the other and for simultaneously disengaging the carriage-feed elements, and automatically-operated means for retarding the reengagement of said feed elements.

21. In a type-writing machine and in a tabulating device the combination of a carriage, a carriage-feed element carried by the carriage, a coöperating carriage - feed element carried by the frame of the machine, a tabulating-stop carried by the frame of the machine, a coöperating tabulating-stop carried by the carriage, spring-restored means for projecting one of said stops in the path of the other and for simultaneously disengaging the carriage-feed elements, and automatically-operated means for counteracting said spring-restored means to retard the reëngagement of said feed elements.
22. In a type-writing machine and in a tabulating device, the combination of a carriage, a carriage-feed element carried by the carriage, a coöperating carriage - feed element carried by the frame of the machine, a tabulating-stop carried by the frame of the machine, a coöperating tabulating-stop carried by the carriage, spring-restored means for projecting one of said stops into the path of the other, and for simultaneously disengaging the carriage-feed elements, and automatically-operated means for counteracting said spring-restored means to retard the reëngagement of said feed elements and to retard the return movement of the projected stop.
23. In a type-writing machine and in a tabulating device, the combination of a carriage, a carriage-feed element carried by the carriage, a coöperating carriage - feed element carried by the frame of the machine, a plurality of denominational stops, a coöperating tabulating-stop, means for projecting one of said denominational stops into the path of the tabulating-stop and for simultaneously disengaging the carriage-feed elements, and automatically-operated means for retarding the reëngagement of said feed elements.
24. In a type-writing machine and in a tabulating device, the combination of a carriage, a carriage-feed element carried by the carriage, a coöperating carriage - feed element carried by the frame of the machine, a plurality of denominational stops, a coöperating tabulating-stop, spring-restored means for projecting one of said denominational stops into the path of the tabulating-stop and for simultaneously disengaging the carriage-feed elements, and automatically-operated means for counteracting said spring-restored means to retard the reëngagement of said feed elements and to retard the return movement of the projected stop.
25. In a tabulating device for type-writing machines, the combination of a carriage, a tabulating-stop, a second coöperating tabulating-stop, means for projecting one of said stops into the path of the other, and a retard ing device which is normally out of engagement with the projectable stop but which is adapted to be automatically engaged thereby when the said stop is moved to the projected position and to retard the return movement thereof.
26. In a tabulating device for type-writing machines, the combination of a carriage, a tabulating-stop, a second coöperating tabulating-stop, spring-restored means for projecting one of said stops into the path of the other, and a spring-restored retarding device which is normally out of engagement with the projectable stop but which is adapted to be automatically engaged thereby when the said stop is moved to the projected position so as to counteract the tension of the spring-restored projecting means.
27. In a tabulating device for type-writing machines, the combination of a carriage, a tabulating-stop, a second coöperating tabulating-stop, means for projecting one of said stops into the path of the other, a retarding device which is normally out of retarding engagement with the projectable stop, but is adapted to be automatically engaged thereby when the said stop is moved to the projected position, and a disengageable carriage-feed mechanism, the disengagement and reëngagement of which is controlled by the projectable stop, whereby the retardation of the return movement of the stop will effect a retardation in the reëngagement of the carriage-feed mechanism.
28. In a tabulating device for type-writing machines, the combination of a carriage, a tabulating-stop, a second coöperating tabulating-stop, means for projecting one of said stops into the path of the other, and a weight which is out of effective coöperation with the projectable stop while said stop is being projected but which is automatically rendered effective during the return movement of said stop to retard said return movement.
29. In a tabulating device for type-writing machines, the combination of a carriage, a tabulating-stop, a second coöperating tabulating-stop, means for projecting one of said stops into the path of the other, a counteracting device to retard the return movement of the projected stop, and a pawl-and-ratchet mechanism interposed between the projected stop and the counteracting device, which pawl-and-ratchet mechanism permits a free movement of the projectable stop to its projected position but throws the counteracting device into coöperation therewith during the return movement of the projected stop.
30. In a tabulating device for type-writing machines, the combination of a carriage, a tabulating-stop, a second coöperating tabulating-stop, means for projecting one of said stops into the path of the other, a weight to retard the return movement of the projected stop, and pawl-and-ratchet mechanism interposed between the projectable stop and the weight, which pawl-and-ratchet mechanism permits a free movement of the projectable stop to its projected position but throws the weight into coöperation therewith during the return movement of the projected stop.
31. In a tabulating device for type-writing machines, the combination of a carriage, a

tabulating-stop, a plurality of denominational stops, means for projecting any of said denominational stops into the path of the tabulating-stop, a counteracting device which coöperates with all of said denominational stops to retard the return movement thereof, and pawl-and-ratchet mechanism interposed between the denominational stops and the counteracting device, which pawl-and-ratchet mechanism permits a free movement of any of the denominational stops to the projected position, but is effective to establish an operative connection between the projected stop and the retarding device during the return movement of said projected stop.

32. In a tabulating device for type-writing machines, the combination of a carriage, a tabulating-stop, a plurality of denominational stops, means for projecting any of said denominational stops into the path of the tabulating-stop, a weight which coöperates with all of said denominational stops to retard the return movement thereof, and pawl-and-ratchet mechanism interposed between the denominational stops and the weight, which pawl-and-ratchet mechanism permits a free movement of any of the denominational stops to the projected position without moving the weight but is effective to establish an operative connection between the projected stop and the weight during the return movement of said projected stop.

33. In a tabulating device for type-writing machines, the combination of a carriage, a tabulating-stop, a second coöperating tabulating-stop, means for projecting one of said stops into the path of the other, a counteracting device, a wheel which operates it, and means controlled by the projectable stop for rotating the wheel during the return movement of the projected stop, to retard said stop in its return movement.

34. In a tabulating device for type-writing machines, the combination of a carriage, a tabulating-stop, a second coöperating tabulating-stop, means for projecting one of said stops into the path of the other, a weight, a wheel which moves said weight and means controlled by the projectable stop for rotating the wheel during the return movement of the projected stop, to retard said stop in its return movement.

35. In a tabulating device for type-writing machines, the combination of a carriage, a tabulating-stop, a second coöperating tabulating-stop, means for projecting one of said stops into the path of the other, a weight which is out of effective coöperation with the projectable stop while said stop is being projected but is automatically rendered effective during the return movement thereof to retard said return movement, and a disengageable carriage-feed mechanism, the disengagement and reengagement of which is controlled by the movement of the projectable stop, whereby the retardation of the return movement of the projected stop will effect an engagement of the carriage-feed mechanism.

36. In a tabulating device for type-writing machines, the combination of a carriage, a tabulating-stop, a second coöperating tabulating-stop, means for projecting one of said stops into the path of the other, a weight to retard the return movement of the projected stop, and pawl-and-ratchet mechanism interposed between the projectable stops and the weight, which pawl-and-ratchet mechanism permits a free movement of the projectable stop to its projected position but throws the weight into coöperation therewith during the return movement of the projected stop, and a disengageable carriage-feed mechanism, the disengagement and reengagement of which is controlled by the movement of the projectable stop, whereby the retardation of the return movement of the projected stop will effect a retardation in the reengagement of the carriage-feed mechanism.

37. In a tabulating device for type-writing machines, the combination of a carriage, a tabulating-stop, a plurality of denominational stops, means for projecting any one of said denominational stops into the path of the tabulating-stop, a counteracting device which coöperates with all of said denominational stops to retard the return movement thereof, pawl-and-ratchet mechanism interposed between the denominational stops and the counteracting device, which pawl-and-ratchet mechanism permits a free movement of any of the denominational stops to the projected position, but is effective to establish an operative connection between the projected stop and the counteracting device during the return movement of any of said projected stops, and a disengageable carriage-feed mechanism, the disengagement and reengagement of which is controlled by the movement of the projectable stop, whereby the retardation of the return movement of the projected stop will effect a retardation in the reengagement of the carriage-feed mechanism.

38. In a tabulating device for type-writing machines, the combination of a carriage, a tabulating-stop, a second coöperating tabulating-stop, means for projecting any one of said stops into the path of the other, a weight, a wheel which moves said weight, means controlled by the projectable stop for rotating the wheel during the return movement of the projected stop to retard said stop in its return movement, and a disengageable carriage-feed mechanism, the disengagement and reengagement of which is controlled by the movement of the projectable stop, whereby the retardation of the return movement of the projected stop will effect a retardation in the reengagement of the carriage-feed mechanism.

39. In a tabulating device for type-writing machines, the combination of a carriage, a tabulating-stop, a second coöperating tabulating-stop, means for projecting any one of said stops into the path of the other, a weight, a wheel which moves said weight, means controlled by the projectable stop for rotating the wheel during the return movement of the projected stop to retard said stop in its return movement, and a disengageable carriage-feed mechanism, the disengagement and reengagement of which is controlled by the movement of the projectable stop, whereby the retardation of the return movement of the projected stop will effect a retardation in the reengagement of the carriage-feed mechanism.

40. In a type-writing machine and in a tabulating device therefor, the combination with a carriage, of a tabulating-stop thereon, key-

actuated denominational stops coöperating therewith, a feed-rack carried by the carriage, a coöperating feed element carried by the frame of the machine, means for disengaging 5 the said feed-rack and its coöperating feed element one from the other when any denominational stop is actuated, and means for retarding the return movement of the denominational stops and the reengagement of the rack and its coöperating feed element.

40. In a type-writing machine and in a tabulating device therefor, the combination with a carriage, of an adjustable tabulating-stop thereon, spring-restored key-actuated denominational stops coöperating therewith, a feed-rack carried by the carriage, a coöperating feed-pinion carried by the frame of the machine, means for disengaging the said feed-rack from its coöperating feed-pinion when 20 any denominational stop is actuated, and an automatically-operated retarding device which counteracts the spring-pressure of the denominational stops, for retarding the return movement of the denominational stops and 25 the reengagement of the rack and its coöperating feed-pinion.

41. In a tabulating device for type-writing machines, the combination of a carriage, a stop carried by said carriage, a second stop 30 coöperating with the carriage-stop, said stops being normally out of the path of each other, means for projecting one of said stops into the path of the other, means for limiting the speed of the return movement of the projected stop, and means for regulating said limiting means to effect a change in the speed of the return movement of the projected stop.

42. In a tabulating device for type-writing machines, the combination of a carriage, a tabulating-stop, a second coöperating tabulating-stop, means for projecting one of said stops into the path of the other, a weight 40 which is out of effective coöperation with the projectable stop while said stop is being projected but is automatically rendered effective 45 during the return movement of said stop to retard its return movement, and means for regulating said weight so as to effect a change in the speed of the return movement of the 50 projected stop.

43. In a tabulating device for type-writing machines, the combination of a carriage, a tabulating-stop carried thereby, a second tabulating-stop coöperating with said first-mentioned stop, means for projecting one of said 55 stops into the path of the other, retarding means comprising a rod having a flexible portion, a weight secured to the rod, and means for automatically and operatively connecting 60 the projected stop and the rod so that the weight will tend to retard the return movement of the projected stop.

44. In a type-writing machine, the combination of a carriage, feed mechanism therefor, means for disengaging the said carriage-feed mechanism and automatically-acting means for affording a retarded movement of

the carriage-feed mechanism during the re-engaging movement thereof.

45. In a type-writing machine and in a tabulating mechanism therefor, the combination of a carriage, carriage-feed mechanism, means for releasing the said carriage-feed mechanism, means for arresting the carriage at a predetermined point in its travel, and means for retarding the movement of the carriage-feed mechanism during the reengaging movement thereof.

46. In a type-writing machine and in a tabulating mechanism therefor, the combination of a carriage, carriage-feed mechanism, means for releasing the said carriage-feed mechanism, a movable device for arresting the carriage at a predetermined point in its travel, and means for retarding the movement of the carriage-feed mechanism and for retarding the movement of the arresting device during the movement of the latter to its normal position.

47. In a type-writing machine, the combination of a carriage, feed mechanism therefor, means for separating the members of the feed mechanism to permit the carriage to run unrestrainedly toward the left, and means acting only on the release of the means for separating the members of the carriage-feed mechanism, for retarding the reengagement of said members of the carriage-feed mechanism.

48. In a type-writing machine, the combination of a carriage, feed mechanism therefor, a key which when operated will separate the members of the feed mechanism and will maintain such separations as long as the key is pressed upon, and means which come into action after the release of said key from pressure for retarding the reengagement of said members of the carriage-feed mechanism.

49. In a type-writing machine and in a tabulating mechanism, the combination of a carriage, feed mechanism therefor, coöperating stop devices, key mechanism for separating the members of the carriage-feed mechanism and for bringing the stop devices into coöperative relation and retarding means adapted to be automatically coupled with or connected to said key mechanism when the latter is actuated to release the carriage and bring the stops into coöperative relation, whereby when the said key mechanism is released by the finger of the operator the parts are caused to return to their normal positions with a retarded motion.

50. In a type-writing machine and in a tabulating mechanism, the combination of a carriage having a stop, carriage-feed mechanism, a coöperating stop adapted to be moved into the path of travel of the stop on the carriage, said coöperating stop having a cam and a notch, and a retarding mechanism including a spring-pressed catch adapted to be actuated by and engaged with said stop so as to connect or couple the latter with the said retarding mechanism when the stop has been

moved into the path of travel of the stop on the carriage.

51. In a type-writing machine and in a tabulating mechanism, the combination of a carriage having a stop, a plurality of denominational stops each having a cam and a notch, and a retarding mechanism including a spring-pressed transverse bar common to all of said denominational stops.

52. In a type-writing machine and in a tabulating mechanism, the combination of a carriage having a stop, carriage-feeding mechanism, a series of denominational stops each having a cam and a notch, connections between said stops and said carriage-feeding

devices, whereby when any one of the denominational stops is projected the carriage-feeding devices are separated, vibratory arms carrying a spring-pressed cross-bar adapted to be acted upon by said denomination-stops, 20 a retarding device, and connections between said arms and said retarding device.

Signed at borough of Manhattan, city of New York, in the county of New York and State of New York, this 1st day of November, 25 A. D. 1901.

CHARLES H. SHEPARD.
